UNITED STATES PATENT OFFICE.

G. HOWLETT DAVIS, OF WASHINGTON, DISTRICT OF COLUMBIA.

PAPER-FEEDING MACHINE.

SPECIFICATION forming part of Letters Patent No. 387,582, dated August 7, 1888.

Application filed September 22, 1886. Serial No. 214,293. (No model.)

To all whom it may concern:

Be it known that I, G. HOWLETT DAVIS, a citizen of the United States, residing at Washington, in the District of Columbia, have invented certain new and useful Improvements 5 in Paper-Feeding Machines, of which the following is a specification.

My invention relates to that class of paper-feeding machines which feed separate sheets of 10 paper, and has for its object to provide a simple, inexpensive, and practical construction to accomplish the purposes herein set forth.

I have chosen to show my invention in connection with a type-writing machine, in order 15 to describe and illustrate the most difficult application of a paper-feeding machine—that is, with a machine so constructed that its platen revolves and also moves to the right and left.

In the accompanying drawings, Figure 1 is 20 a side view of my improvements, showing the separating device attached to the carriage of a type-writing machine and the feed-table supported from the frame of said machine. Fig. 2 is a plan view showing the relative positions 25 of the improvements with the paper-carriage of the type-writing machine drawn to the extreme right. Fig. 3 is a rear elevation of the same, showing fully the construction and arrangement of these several rear parts of the type-writing machine and my improvements.

Similar letters of reference indicate like parts throughout the several views.

A is an inclined feed-table provided with paper-rests B, paper-guides C D, and shaft-clamps F, the whole moving simultaneously 30 with lever J.

The paper-rests B, made to slide through 35 projections B², can be drawn out to support a large supply of paper. The springs B³, screwed to the feed-table at points B⁴ and hooked to the rear ends of paper-rests B, are of sufficient 40 tension to draw back on the said paper-rests and keep the teeth B' and fingers B⁵, which are rigidly attached to the projecting ends of the 45 paper-rests, against the bottom and outside edge of a variable supply of paper resting on the arms of the said paper-rests. The fingers B⁵ are elastic and assist in preventing more 50 than one sheet from rising at a time by taking a frictional hold on the second sheet as soon as the lower edge of the outside sheet has been

raised beyond their ends, which are sharpened flat.

The paper-guides C D are adjusted to suit the height and width of paper being fed by 55 means of slotted strips C' D', which are screwed to the feed-table A, so as to pass over the inside edges of the notches made therein, and the slotted strips C' D', bent at right angles, so that when the slotted ends cross the strips C' D' 60 the other ends project beyond the face of the feed-table A and are adjusted and held in position by the thumb-screws C' D', which pass through the opening made where the two slotted strips cross each other to a nut on the 65 opposite side, thus clamping the angular strips to the stationary strips in any position. By loosening the thumb-screws they can be moved in the slots of the stationary strips, or the movable right-angular strips infolding them can be 70 moved in or out to suit the size of the paper being fed. The cross-arms C extend over the table for the purpose of preventing the paper falling forward off the said table when it is returned to its normal position.

In order to allow a sheet of paper being fed 75 into the carriage of a type-writing machine to move freely to the left with it, the guide P, of the shape shown, is mounted on the carriage of the said machine by means of a clamp-screw, 80 the upper portion of the said guide being bent so as to guide the lower left-hand edge of the paper into the feed. A lower left-hand guide placed on the feed-table would prevent the top 85 of the separated sheet from moving to the left with the carriage.

The spring-rod E is made to work through pivot E, which turns in clamp E³, screwed on arm H, the lower end, E⁴, of rod E' being bent to pass through lever J at point J'. The spring 90 E², attached to pivot E and the lower end of the rod E', is shown slightly drawn in Fig. 1, caused by the backing tendency of the feed-table and lever J while in their normal position. This construction is so arranged on the 95 arm H with reference to the lever J that a contraction of the spring E² is caused while the spring-rod E' is passing the vertical, and the said spring is elongated and pulls back on the said lever after it has reached a certain point. 100 Owing to the expansion of the spring E² directly after the spring-rod E' passes the vertical,

the movement of the lever and feed-table is accelerated about the time the paper reaches the separating device. This accelerated movement is desirable, but not essential, and therefore the device described might be dispensed with by employing a simple device for stopping the backward movement of the feed-table.

The shaft-clamps F are screwed to the feed-table A and clamp the shaft G by means of thumb-screws F', which work through to grooves G' in shaft G.

Arms H H', of the shape shown, are ridged longitudinally at their lower ends, H², to prevent them from turning in the corrugated openings I³, made through angle-clamps I, (see Fig. 2,) and by raising or lowering the said arms and securing them by the thumb-screws I' the feed-table is adjusted at will. The feed-table may also be adjusted parallel with the paper-carriage by resetting the arm H' in the angle-clamp I, thus changing the position of its top end upon which the feed-table rests.

The angle-clamps I are permanently and rigidly attached to the frame of the writing-machine by means of the screws I², which work through screw-holes already made for securing the rail-standards to the frame of writing-machine.

The lever J, wedged to shaft G, is extended to the front of the writing-machine to a position where it can be conveniently grasped by the hand of the operator.

The bridge-arms K are securely attached to the carriage-rod Z of the writing-machine by means of the clamps K'.

The slots L are formed in the arms K for the reception of the ends N² of bar N, and the slots are so inclined with respect to the movement of the lower edge of the feed-table A that the friction-surface of the clearing-plate M is caused to rub upward against the supply of paper so long as the feed-table advances, and when the feed-table recedes the bar N from the force of gravity slides down the slots L to its normal position.

The bar N is provided with a number of screw-pins, N', the points of which are made to project beyond the face of the said bar by turning them from the back. The ends N² of the bar N are made to fit closely in the slots L, thus keeping the said bar in proper position whether stationary or moving.

The clearing-plate M is adjusted on the bar N by two pins projecting from the rear of the clearing-plate and passing through two holes in the said bar, the said pins being provided at their ends with small nuts, which are adjusted loosely in order to allow a slight movement of the said pins and clearing-plate when the latter is pressed against the bar N. Small holes are made through the clearing-plate opposite the points of the screw-pins N', so that the said pins may be adjusted to project through their respective holes when the clearing-plate is pressed, thus causing the points of

the said pins to indent or slightly prick the first sheet of paper on the feed-table, and this, together with the friction of the clearing-plate, is sufficient to raise the thickest or heaviest sheet of paper. The clearing-plate, or that part of it which comes in contact with the paper, is made frictional by roughening its surface or by padding or constructing it of rubber or other suitable material. Ordinarily the friction alone on a sheet of paper is sufficient to raise it; but the aid of the pin-points is essential when smooth or heavy paper is being fed.

The buffer-springs O are arranged on the arms K, so as to impede the upward movement of the bar N should it happen to be forced back too far.

The operation of my improvements is as follows: A supply of paper—say one hundred sheets—is placed on the feed-table A by drawing out the paper-rests B and adjusting the side guides, C, D, and P. The carriage of the writing-machine being drawn to the right, as is always done to commence a line, the fore-finger is extended back and a quick pull given the lever J, which causes the lower portion of the feed-table to advance, bringing the outside sheet of the supply of paper resting thereon in contact with the clearing-plate, thereby causing the points of the screw-pins N' to protrude through the openings in the clearing-plate and indent or prick the said sheet and forcing the bar N, with the clearing-plate, up the slots L. Owing to the inclination of the slots L with respect to the movement of the opposite portion of the feed-table an upward rubbing of the clearing-plate against the outside sheet of paper is produced, and this, aided by the frictional hold of the points of the pins N', raises the sheet above the points of the teeth B' and the fingers E⁵, which prevent the second sheet from rising by taking a frictional hold on it as soon as the lower edge of the first sheet is raised above them. The bottom edge of the first sheet left on the feed-table is always sufficiently raised above the one next it—which is owing to the increased curvature of the arms of the paper-rests near the teeth or projecting end and the upward rubbing against it by the last sheet raised—to allow the points of the said teeth and fingers to hold the second sheet and the balance of the paper on the feed-table while the last sheet is being raised. When the feed-table recedes, the bar N slides down the slots L until suddenly stopped, which throws the clearing-plate from it against the raised sheet sufficient to detach it should it be hanging on the points of the pins N'. The separated sheet now drops and is directed by the guides C, D, and P onto the feed-roller X, the top of the sheet being below the guides C. The sheet in this position is ready to be directed at will around the platen by the feed-roller X and guides X' and moves freely to the right and left with the carriage.

It is estimated that the entire operation of

feeding a sheet from the supply on the feed-table to the feed-roller of the writing-machine can be accomplished in less than two seconds.

- It is obvious that my invention contemplates an extended application by arranging the feed-table to be operated automatically and to feed a separate sheet at the proper time to any fixed point—such as the platens, cylinders, &c.—of printing, ruling, and other machines.
- 10 By making the face of the bar N employed in my separating device frictional the screw-pins N' and the clearing-plate M might be dispensed with, especially when thin rough paper only is intended to be fed.

15 What I claim is—

1. In a paper-feeding machine, the combination of a feed-table mounted upon pivotal bearings and provided with mechanism for swinging the same, substantially as described, and a bar provided with screw-pins the points of which project from its face, the ends of the said bar being mounted in bearing-slots set at an angle to the line of movement of the said table, whereby when the said bar is impinged upon by the said table it moves up the face of the same, substantially as set forth.
2. In a paper-feeding machine, the combination of a feed-table pivotally mounted upon a frame, paper-rests set in perforated projections, teeth mounted upon the ends of the said arms adapted to impinge upon the said paper, and a spring attached to the other end of the said arms and adapted to draw the same toward the table, substantially as set forth.
3. In a paper-feeding machine, the combination of a feed-table mounted upon pivotal bearings, substantially as described, paper-rests, substantially as described, secured to the said table, and a separating device placed

in the line of movement of said table and adapted to move up the face of same when impinged upon, substantially as set forth.

4. In a paper-feeding machine, the combination of a feed-table mounted upon pivotal bearings, substantially as described, a lever attached rigidly to the said table and provided with a handle within convenient reach of the operator, and a regulating device consisting of a pivot working in a socket formed by clamps rigidly attached to one support of the feed-table, a rod loosely mounted in a perforation at the outer end of the said pivot, and a spiral spring infolding the said rod and secured to the end thereof and to the said pivot, substantially as and for the purpose set forth. 55

5. In a paper-feeding machine, a device for separating one sheet from a supply, consisting of a rod provided with a row of screw-pins and mounted in oblique slots at either end, said slots being set at an angle to the line of movement of the said feed-table, whereby when the said table impinges the said bar the latter is caused to move upward against the face of the said table, substantially as described. 6c

6. In a paper-feeding machine, the combination of the carriage of a printing-machine, substantially as described, two arms mounted thereon and provided with slots set at an angle to the line of movement of a feed-table, a bar provided with screw-pins and mounted in the said slots in the said arms, and a feed-table adapted to move forward against the said bar, substantially as described. 7c 65
